UNITED STATES PATENT OFFICE.

CLARENCE J. BARLEY, OF ALTOONA, PENNSYLVANIA.

PISTON-VALVE.

1,080,945.

Specification of Letters Patent.

Patented Dec. 9, 1913.

Application filed March 28, 1913. Serial No. 757,023.

To all whom it may concern:

Be it known that I, CLARENCE J. BARLEY, a citizen of the United States, residing at Altoona, in the county of Blair and State 5 of Pennsylvania, have invented certain new and useful Improvements in Piston-Valves, of which the following is a specification.

This invention relates to the subject of locomotives, and particularly to the piston 10 valves which constitute a part of the locomotive valve gear, while the primary object of the invention is to provide an integral piston valve body, preferably constructed of steel tubing, with the ends thickened and flanged outward for the purpose 15 of engaging the bull ring of the valve.

Another object of this invention is to provide a piston valve body that is free from steam leaks, light and durable and at the 20 same time easily constructed and applied.

A still further object of this invention is to provide an integral valve body with the ends flared outward so as to engage the ledge on the end of the spider, in such manner as to reduce the number of parts associated with a steam piston valve.

With these and many other objects in view, which will be more readily apparent as the nature of the invention is better understood, the same consists of the novel construction, combination and arrangement of parts as will be hereinafter fully pointed out, illustrated and claimed.

The essential feature of the invention is 35 quite susceptible to some variation without departing from the spirit or scope of the invention, but a preferred and thoroughly practical embodiment of the same is shown in the accompanying drawings, in which:—

Figure 1, is a side elevation of the piston valve of the type usually found upon locomotives, embodying my invention. Fig. 2, is an end view of the parts shown in Fig. 1 of the drawings. Fig. 3, is an enlarged sectional view of the valve shown in Fig. 1 of the drawings. Fig. 4, is a longitudinal sectional view of a locomotive steam cylinder, showing my improved piston valve in position.

Like reference numerals designate corresponding parts throughout the several figures of the drawings.

In carrying out this invention no change

is contemplated in the piston valve, other than forming the body 10 integral with the ends 11, the construction heretofore employing two end pieces and a central piece, which were riveted together; this construction having been found unsatisfactory, due to the number of parts, leaky joints and a 60 weak valve stem. One custom usually resorted to for the purpose of eliminating the above named difficulties, is to cast the valve all in one integral piece, but this construction has its disadvantages due to its excessive weight.

This invention successfully eliminates the difficulties experienced with both of the above valve constructions, and contemplates the use of a steel tubing 10, having thickened flanged ends 11, adapted to engage the bull ring 12, in a recess 13, cut concentric with the ring and forming a centering means therefor. The bull rings 12^a are held in spaced relation by the bolts 14, which pass through the hub 15 of the said ring and hold the parts firmly together.

In the construction of this piston valve it is not essential that the central portion 10^a be of a thinner section than the end portion 80 11, but this construction materially reduces the weight, and with the flanged ends thickened in section, the process of flaring and flanging is accomplished without splitting the material, which is invariably the case 85 when a light end section is used.

From the above description it is believed that the many advantages of the herein described piston valve will be quite readily apparent without further elaboration, and

What I claim and desire to be secured by Letters Patent is:—

The combination of a piston valve body having a recessed flanged end whose wall is of greater cross section than the wall of 95 the body of said stem, and a spider fitting in said recess portion, a bull ring held by the spider and means for securing the spider.

In testimony whereof I affix my signature 100 in presence of two witnesses.

CLARENCE J. BARLEY.
